UNITED STATES PATENT OFFICE

CHARLES B. J. MOLITOR, OF FOREST HILLS, NEW YORK, ASSIGNOR TO THOMAS WILSON & CO. INC., OF NEW YORK, N. Y.

DESIGN FOR LACE

Application filed June 2, 1932. Serial No. 43,958. Term of patent 3½ years.

To all whom it may concern:

Be it known that I, CHARLES B. J. MOLITOR, a citizen of the United States, residing at No. 10 Holder Place, Forest Hills, city of New York, county of Queens, State of New York, have invented a new, original, and ornamental Design for Lace, of which the following is a specification, reference being had to the accompanying drawing, forming part hereof.

The drawing shows a face view of a piece of lace embodying my design.

I claim:

The ornamental design for lace, substantially as shown.

CHARLES B. J. MOLITOR.
